THREAD GUIDE

Seddon C. Nelson, Front Royal, Va., assignor to
 American Viscose Corporation, Wilmington,
 Del., a corporation of Delaware

Application October 31, 1944, Serial No. 561,301

14 Claims. (Cl. 28—71.5)

1 This invention relates to a fixed or stationary guide for effecting and controlling lateral displacement of thread wrapped one or more times about a wheel and to prevent the thread from riding on or lapping upon itself. My improved guide is particularly well-adapted for use in connection with artificial filament spinning machines, in which it may serve to prevent slippage of the filamentary material on one or more of such wheels.

It has been found that while fixed guides efficiently prevent riding of the filamentary material on itself, in practice they have many disadvantages, because the thread or the like passing thereover always contacts the same portion of the guide which becomes worn with consequent variations in the tension on the thread which result in variations in strength, dyeing capacities, etc., along the length thereof.

Such guides require frequent replacement. The loss of time incurred in the spinning operation necessitated by replacement of worn guides, the added expense involved in frequent repolishing of the guides and purchase of additional guides, and the loss due to damage of the thread in passing over defective guides all cause an increase in the expense of manufacturing and of the final product.

These difficulties are overcome by the present invention which provides a fixed or stationary guide having a plurality of operating positions, and which can be adjusted as required to present a new surface to thread passing thereover.

In its broader aspects, my improved guide comprises at least two thread guiding portions laterally offset from each other and separated by a shoulder which is polygonal in outline and which may serve to identify the various operating positions of the guide. The thread guiding portions of the guid may be grooved or smooth. The guide proper is supported by a post or rod which may be laterally offset from the thread-guiding portions and which may have any desired cross-sectional configuration but preferably has a cross-sectional configuration corresponding to the polygonal outline of the dividing shoulder.

A thread guide constructed in accordance with my invention is shown in the accompanying drawing, in which

Figure 1 is a front perspective view of a set-up comprising a wheel and guide; and

Figure 2 is a side elevational view of the set-up of Figure 1.

Referring to the drawing, there is shown a wheel 2 of the type commonly employed for

2 handling filamentary material. Disposed beneath the wheel and mounted on a frame (not shown) is a guide 3. The guide comprises a circular thread-guiding portion 4 provided with two annular grooves 5 and 5a and which is laterally offset from a circular thread-guiding portion 6 which may or may not be grooved (Figure 2) and separated therefrom by a dividing shoulder 7 which, in the specific illustration, has the outline of an equilateral triangle, the apices 8 of which are spaced apart 120° about the circumference of the guide. The guide is supported by means of laterally offset rod or post 9, the cross-sectional configuration of which is triangular.

In operation, as for example when the guide is used to effect lateral displacement of freshly spun filamentary material coming from a coagulating bath or other devices on which the material has been subjected to the usual after-treatments, the operator laces up the wheel-guide set-up by passing the thread 10 over the thread-guiding portion 6 of guide 3, and around wheel 2, about which the thread may be wrapped several times to provide traction. The thread is then passed through groove 5 in thread-guiding portion 4 of guide 3, and over wheel 2, after which it is passed through groove 5a in thread-guiding portion 4 of the guide, and again up over wheel 2, from which it passes continuously to another wheel-guide system or to a suitable take-up mechanism (not shown).

The new guide has the advantage that it is symmetrical and can be used with equal effectiveness in a plurality of positions. When the operator observes that the portion of the guide over which the thread is traveling is beginning to show wear, it is a simple matter to adjust the position of the guide so that a fresh portion of the surface thereof is presented to the thread. In the case illustrated in Figures 1 and 2, where the dividing shoulder 7 has the outline of an equilateral triangle, one of the projections thereof, near its apex, is provided with an identifying spot of contrasting color, 11. If, at the start of operation, the guide is so positioned that the projection bearing mark 11 is in the upright position, the position of the guide may be changed to bring the other two apices of the triangle into upright position, in sequence, as required. Instead of placing a spot of contrasting color near the apex of one of the projections, one or all of the apices of the triangle represented by the shoulder may be differently colored, or sequentially numbered, or other types of indicia may be provided. It

will be understood, of course, that dividing shoulder 7 does not have to be triangular in outline but may be of other polygonal outline, such as quadrilateral, rectangular, square, hexagonal, etc. Further, the guide may comprise more than two thread-guiding portions each of which is separated from the other by a dividing shoulder.

The thread-guiding portions 4 and 6 may be grooved or ungrooved, and portion 4 may be of the same diameter throughout or the diameter thereof may be progressively larger or progressively smaller along the length thereof extending from shoulder 7. If either or both of the thread-guiding portions 4 and 6 are provided with annular grooves, the pitch of the sides and the depth of the grooves may be of any degree or dimension, but preferably, the grooves are comparatively shallow, which makes for easy polishing and lacing-up.

The new guide has many advantages as compared with fixed guides available heretofore. Thus, in use, the wear thereon is uniformly distributed around the circumference of the thread-guiding portions, thereby greatly prolonging the length of time during which the guide will perform its function satisfactorily, beyond that of the fixed guides now in use, while ensuring continuous delivery of the thread under a constant uniform tension. For example, when, as in the case with the guide illustrated in Figures 1 and 2, the guide has three effective operating positions as defined by the apices of the equilateral triangle outlined by shoulder 7, the guide may be used three times longer than a guide of conventional design, before replacement thereof becomes necessary.

The guide may be cast or molded in one piece, or it may be formed from separate elements comprising the guide proper and the supporting post or rod, which elements may be joined together in any suitable manner.

The guide may be made of any desirable hard and rigid material which is resistant to acids, alkalies, and other chemical solvents that may be present on the filamentary material. For example, it may be made of porcelain, glass, plastic materials, as for instance, synthetic resins such as polyvinyl resins, for example, polyvinyl chloride, polystyrene, phenol-formaldehyde resins, phenol-furfural resins, methacrylate polymers, synthetic rubber, or hard rubber itself.

While preferred embodiments of the invention have been shown and described, it is not intended that the invention be limited thereto, and modification may be made within the scope of the appended claims.

I claim:

1. A stationary guide for filamentary material comprising two circular thread-guiding portions laterally offset with respect to each other, at least one annular groove in the portion having the greater diameter, a dividing shoulder having the outline of an equilateral triangle separating said portions, and a support for the guide comprising a laterally offset post-like member having, in cross-section, the configuration of an equilateral triangle.

2. In combination, a wheel for handling filamentary material, and a stationary guide to cause lateral displacement of a thread wrapped one or more times around the wheel and prevent riding of the thread on itself, said guide comprising two thread-guiding portions laterally offset with respect to each other, the portion having the great-

est diameter being provided with at least one annular groove, and said portions being separated by a dividing shoulder having the outline of an equilateral triangle, the apices of which define a plurality of operating positions for said guide.

3. A stationary guide for filamentary material, said guide having a plurality of operating positions, and comprising at least two thread-guiding portions laterally offset with respect to each other and separated by a dividing shoulder having a polygonal outline, each angle of the polygon comprising the shoulder defining one of the operating positions for the guide.

4. A stationary guide for filamentary material, said guide having a plurality of operating positions, and comprising at least two thread-guiding portions laterally offset with respect to each other and separated by a dividing shoulder having a triangular outline, each apex of the triangle comprising the shoulder defining one of the operating positions for the guide.

5. A stationary guide for filamentary material, said guide having a plurality of operating positions and comprising at least two thread-guiding portions laterally offset with respect to each other and separated by a dividing shoulder having the outline of an equilateral triangle, each apex of the triangle comprising the shoulder defining one of the operating positions for the guide.

6. A stationary guide for filamentary material, said guide having a plurality of operating positions and comprising at least two circular thread-guiding portions laterally offset with respect to each other and each having at least one annular groove therein, said portions being separated by a dividing shoulder having a polygonal outline, each angle of the polygon comprising the shoulder defining one of the operating positions for the guide.

7. A stationary guide for filamentary material, said guide having a plurality of operating positions and comprising two circular thread-guiding portions laterally offset with respect to each other, the portion of greater diameter having at least one annular groove therein, said portions being separated by a dividing shoulder having a polygonal outline each angle of the polygon comprising the shoulder defining one of the operating positions for the guide.

8. A stationary guide for filamentary material, said guide having a plurality of operating positions and comprising two circular thread-guiding portions laterally offset with respect to each other, the portion of greater diameter having at least one annular groove therein, said portions being separated by a dividing shoulder having the outline of an equilateral triangle, each apex of the triangle comprising the shoulder defining one of the operating positions for the guide.

9. A stationary guide for filamentary material, said guide having a plurality of operating positions and comprising at least two thread-guiding portions laterally offset with respect to each other and separated by a dividing shoulder having a polygonal outline, each angle of the polygon comprising the shoulder defining one of the operating positions for the guide, said guide being supported by a laterally offset post-like member the cross-sectional configuration of which corresponds to the polygonal outline of said shoulder.

10. In combination, a wheel for handling filamentary material, and a stationary guide to cause lateral displacement of a thread wrapped one or more times around the wheel and prevent riding

of the thread on itself, said guide having a plurality of operating positions and comprising at least two thread-guiding portions laterally offset with respect to each other and separated by a dividing shoulder having a polygonal outline, each angle of the polygon comprising the shoulder defining one of the operating positions for the guide.

11. In combination, a wheel for handling filamentary material, and a stationary guide to cause lateral displacement of a thread wrapped one or more times around the wheel and prevent riding of the thread on itself, said guide having a plurality of operating positions and comprising at least two thread-guiding portions laterally offset with respect to each other and separated by a dividing shoulder having a triangular outline, each apex of the triangle comprising the shoulder defining one of the operating positions for the guide.

12. In combination, a wheel for handling filamentary material, and a stationary guide to cause lateral displacement of a thread wrapped one or more times around the wheel and prevent riding of the thread on itself, said guide having a plurality of operating positions and comprising at least two thread-guiding portions laterally offset with respect to each other and separated by a dividing shoulder having the outline of an equilateral triangle, each apex of the triangle comprising the shoulder defining one of the operating positions for the guide.

13. In combination, a wheel for handling filamentary material, and a stationary guide to cause lateral displacement of a thread wrapped one or more times around the wheel and prevent riding of the thread on itself, said guide having a plurality of operating positions and comprising at least two thread-guiding portions laterally offset with respect to each other and separated by a dividing shoulder having a polygonal outline, each

angle of the polygon comprising the shoulder defining one of the operating positions for the guide, and a support for the guide comprising a post-like member having in cross-section a polygonal configuration.

14. In combination, a wheel for handling filamentary material, and a stationary guide to cause lateral displacement of a thread wrapped one or more times around the wheel and prevent riding of the thread on itself, said guide having a plurality of operating positions and comprising two thread-guiding portions laterally offset with respect to each other, the portion having the greatest diameter being provided with at least one annular groove, and said portions being separated by a dividing shoulder having a polygonal outline, each angle of the polygon comprising the shoulder defining one of the operating positions for the guide.
